UNITED STATES PATENT OFFICE.

JAMES F. O'SHAUGHNESSY, OF NEW YORK, N. Y., ASSIGNOR TO NELSON O'SHAUGHNESSY, OF VIENNA, AUSTRIA-HUNGARY.

MACHINE FOR GATHERING COTTON.

No. 889,958.

Specification of Letters Patent.

Patented June 9, 1908.

Application filed November 4, 1907. Serial No. 400,464.

To all whom it may concern:

Be it known that I, JAMES F. O'SHAUGHNESSY, a citizen of the United States, residing in the city, county, and State of New York, have made a certain new and useful Invention in Machines for Gathering Cotton, of which the following is a specification.

This invention relates to machines for gathering cotton.

10 The object of the invention is to provide a machine which is simple in construction and efficient in operation for facilitating the gathering of cotton.

A further object is to provide a machine 15 of the character referred to wherein provision is made for receiving the cotton as picked by a large number of operators, as the machine is progressed through the field, and conveying the same into a receptacle forming part of the machine.

Other objects of the invention will appear more fully hereinafter.

The invention consists substantially in the construction, combination, location and relative arrangement of parts, all as will be more fully hereinafter set forth, as shown in the accompanying drawings, and finally pointed out in the appended claims.

Referring to the accompanying drawings, 30 and to the various views and reference signs appearing thereon,—Figure 1 is a view in side elevation of a machine embodying the principles of my invention. Fig. 2 is a view in rear elevation of the same. Fig. 3 is a view in top plan, parts broken off. Fig. 4 is a broken detail view in section on the line 4, 4, Fig. 3. Fig. 5 is a broken detail view in section on the line 5, 5, Fig. 3. Fig. 6 are broken detail views respectively in section 35 on the line 6, 6, Fig. 3, and in top plan. Fig. 7 is a broken detail view, parts in section on the line 7, 7, Fig. 5.

The same part is designated by the same reference sign wherever it occurs throughout the several views.

Experience has demonstrated that the most reliable method of picking cotton is with the human hands. This method, however, is slow and tedious, and imposes great trial upon the operators, especially where such operators provide themselves with bags strapped over their shoulders to receive the cotton as picked. In such case the operator is required to stoop or bend over to pick the

cotton, and then to straighten up in order to 55 deposit the picked cotton in the bag. Moreover, the increasing quantity of cotton in the bag, as the operator advances along the row of cotton stalks, imposes an increasing weight upon the operator, and very materially 60 circumscribes his daily capacity. In my Patent No. 843,294, issued to me Feb. 5, 1907, I have shown described and claimed a cotton gathering machine designed to relieve the operator of the physical wear, tear 65 and fatigue incident to the constant bending or stooping over and straightening up, and of the labor of carrying the picked cotton, and wherein is employed a vehicle adapted to be progressed through the cotton fields 70 and along the rows of cotton stalks, and having a receptacle with trailing carriers arranged to be pushed or to be drawn along between adjacent rows of cotton stalks, and having carrier belts to receive the picked 75 cotton from the hands of the operators and to deliver the same into the receptacle:

It is among the special purposes of the present invention to provide a machine of this character with means for accommodating larger numbers of operators whereby the work of harvesting the cotton crop is very greatly facilitated and more quickly accomplished than has been possible heretofore.

In carrying out my present invention, I 85 propose to employ a vehicle having a body receptacle and carriers trailing from the rear end thereof, and delivering into such body receptacles. And I also propose to employ carriers extending horizontally and laterally 90 from one or both sides of the body receptacle and transversely of the rows of cotton stalks, and upon which the cotton when picked by the operators may be deposited and delivered thereby into the receptacle. 95 I also propose to provide such laterally extending horizontal carriers, when so desired, with trailing carriers arranged to operate between adjacent rows of cotton stalks and upon which the cotton, when picked, is 100 thrown by the operators, and is thereby deposited upon the laterally extending horizontal carrier and thence carried and delivered into the body receptacle.

The vehicle comprises a body receptacle 105 A, mounted upon wheels B, whereby it may be conveniently progressed through the cotton field and preferably lengthwise of the

rows of cotton stalks. The means for progressing the machine are unimportant, so far as the present invention is concerned. In the particular form shown, however, but to 5 which my invention is not to be limited or restricted, I employ a motor vehicle, the motor C, serving to drive the rear axle from which the various carriers are operated.

Suitably hinged or pivoted to the upper 10 edge of the rear end of the receptacle are trailer frames D, arranged to trail rearwardly therefrom and between adjacent rows of cotton stalks, and each having a traveling belt E, adapted to be driven in any suitable. 15 manner, as, for instance, by means of a sprocket chain F, from the rear axle. The operators gather or pick the cotton from the stalks and throw the same onto the belts E, by which it is elevated and delivered into the 20 body receptacle.

On one or both sides of the body receptacle and extending horizontally and laterally therefrom transverse to the rows of cotton stalks and above the same is a frame G, 25 on which operates a traveling carrier belt H, adapted to be driven in any suitable manner, as for instance, by means of gearing, indicated at J, from the rear axle. This carrier is designed to receive the picked cotton 30 from the hands of the operators, and to deliver the same into the body receptacle. To this end the belt H, operates around a drive roller K, at the outer end of the horizontal frame G, and, at the inner end of said frame 35 is designed to deliver the cotton into the body receptacle in any suitable or convenient manner, as for instance, by being led around guide rollers L, and thence vertically along the side of the body receptacle, and over 40 guide rollers M and N. The roller N is arranged inside the rollers M, with reference to the top edge of the body receptacle, so as to deflect the carrier inwardly over the body receptacle, thereby enabling the picked cotton 45 to fall therefrom into the receptacle A, as the belt travels around said roller N. In order to prevent the cotton from falling off the carrier belt during the vertical travel thereof, I provide the carrier belt with ribs 50 or cleats O, or other suitable devices, to retain the cotton thereon, and I also arrange a vertical shield P, to inclose the vertical portion of the carrier belt, such shield being cut away or omitted at the upper inner end 55 thereof, as indicated at R, Fig. 5. In order to enable the belt to be properly deflected into its vertical and horizontal directions at the inner end of the frame G, without interference from or with the cleats or ribs O, I 60 arrange said guide rollers L, to engage the carrier belt only at the edges thereof, as most clearly shown in Figs. 4 and 7.

In the operation of the machine so far described, the vehicle is slowly progressed along 65 or lengthwise of the rows of cotton stalks

with the horizontal carriers extending out laterally over and above and transversely with respect to the rows of stalks, being braced in any suitable manner, as for instance by the brace rods S, connected at one end to 70 the outer end of the horizontal carrier frames and at the other end to the vehicle body. Where the cotton stalks are not too high the horizontal carriers may be maintained at a sufficient height for the operators to directly 75 deposit the cotton thereon as it is picked from the open bolls, such cotton being conveyed to and delivered into the body receptacle A, by the carrier belt.

It may be desirable to maintain the horizontal carriers at such a height as to make it 80 inconvenient to deposit the picked cotton thereon direct from the hands of the operators, and especially where the cotton stalks are tall and the danger is incurred of breaking them down or injuring them or the unopened bolls of cotton thereon. In such case I propose to provide trailing carriers, for the horizontal carriers, said trailing carriers extending rearwardly from the horizontal carrier 85 and operating between adjacent rows of cotton stalks. These trailing carriers, in the particular form shown, to which, however, the invention is not to be limited or restricted, consist of frames A', suitably connected at 90 their upper ends to the rear edge or side of the horizontal carriers G. In practice a convenient arrangement is to support the upper ends of the trailer carriers A', upon a shaft 95 B', journaled in bearing carried by the horizontal frame and extending longitudinally thereof, said shaft forming part of the gearing for driving the horizontal carrier belts or conveyers H. From their points of connection with the rear edge or side of the horizontal frames, these trailer frames extend rearwardly and downwardly, parallel to the 100 rows of cotton stalks, each trailer frame operating in the space between the adjacent rows. The trailer frames may be supported 105 at their lower ends in any suitable or convenient manner. I have shown these frames braced by tie rods 6', but it is obvious that the invention is not limited or restricted in this respect. Traveling belts or conveyers D', 110 operate over rollers supported by the trailer frames at the respective upper and lower ends thereof, the rollers E', at the upper ends of the trailer frames being mounted up on the shafts B', and driven thereby. The shafts 115 B', and the rollers E', are arranged in such relation to the horizontal carriers as to enable the cotton placed upon the trailing carriers to be delivered thereby upon the horizontal carriers and thence carried and deposited into the body receptacle A. If desired, the trailing carriers D', may be provided with cleats or other form of retaining devices F', for retaining the cotton deposited upon such carriers by the operators while it 120 125 130

is being elevated to the horizontal carriers H. In the operation of this feature of my invention the operators pick the cotton by hand from the opened bolls, as the machine progresses slowly through the field, and deposit the picked cotton upon the trailing carriers by which it is elevated and delivered onto the horizontal carriers and is delivered thereby in to the body receptacle. The trailing carriers being inclined downwardly and rearwardly enable the operators to readily pick and deposit the cotton thereon without the necessity of unduly raising or straightening up and bending over. Moreover, since the cotton picking season is comparatively short and the need for cotton picking labor during such season, very great, a machine embodying the principles of my invention permits the employment of a larger number of operators, of all sizes and ages thereby enabling the cotton to be harvested quickly and without imposing the physical fatigue, wear and tear upon the individuals, which is the greatest difficulty encountered in the ordinary manual cotton picking operation.

Having now set forth the object and nature of my invention and a construction embodying the principles thereof, and having explained such construction, its purpose, function and mode of operation, what I claim as new and useful and of my own invention and desire to secure by Letters Patent is:

1. In a machine for gathering cotton, a vehicle adapted to be advanced along the cotton rows, and having a body receptacle, in combination with a horizontal frame extending laterally from the side of said body receptacle, trailing carriers extending rearwardly from said horizontal frame and operating between adjacent rows of cotton stalks, said trailing carriers adapted to receive the cotton when picked and to deliver the same upon said horizontal frame and means for conveying the cotton from said horizontal frame to and delivering the same into said body receptacle.

2. In a machine for gathering cotton, a vehicle adapted to be advanced along the cotton rows, and having a body receptacle, in combination with a horizontal frame extending laterally from the side of said receptacle, a carrier operating thereon and delivering into the receptacle, frames connected to the rear edge or side of said horizontal frame and trailing rearwardly therefrom, carriers operating on said trailing frames and de-

livering to said first mentioned carriers, and means for operating said carriers.

3. In a machine for gathering cotton, a vehicle, adapted to be advanced along the cotton rows, and having a body receptacle, in combination with a horizontal frame extending laterally from the side of said receptacle, a carrier mounted on said frame, and operating horizontally lengthwise thereof, guides for deflecting said carrier vertically along the side of said receptacle, and guides for deflecting said carrier inwardly over the top edge of said receptacle, and means for operating said carrier.

4. In a machine for gathering cotton, a vehicle adapted to be advanced along the cotton rows, and having a body receptacle, in combination with a horizontal frame extending laterally from the side of said receptacle, a carrier mounted on said frame and operating horizontally lengthwise thereof, guides for deflecting said carrier vertically along the side of said receptacle and guides for deflecting said carrier inwardly over the top edge of said receptacle, a shield for the vertically extending part of said carrier, and means for operating said carrier.

5. In a machine for gathering cotton, a vehicle adapted to be advanced along the cotton rows, and having a body receptacle, and trailing carriers extending rearwardly and downwardly from the rear end of and delivering into said receptacle, in combination with a horizontal carrier extending laterally from the side of said receptacle, and arranged to deliver into said receptacle.

6. In a machine for gathering cotton, a vehicle adapted to be advanced along the cotton rows, and having a body receptacle, and trailing carriers extending rearwardly and downwardly from the rear end of and delivering into said receptacle, in combination with a horizontal carrier extending laterally from the side of and delivering into said receptacle, trailing carriers extending rearwardly and downwardly from and delivering upon said horizontal carrier, and means for operating said several carriers.

In testimony whereof I have hereunto set my hand in the presence of the subscribing witnesses, on this 31st day of October A. D., 1907.

JAMES F. O'SHAUGHNESSY.
